ROCK DRILL ROTATION MECHANISM

Earl B. Lear, Garfield Heights, Ohio, assignor, by
mesne assignments, to The Cleveland Pneumatic
Tool Company, Cleveland, Ohio, a corporation
of Ohio

Application December 3, 1942, Serial No. 467,753

4 Claims. (Cl. 121—7)

The present invention relates broadly to fluid actuated rock drills of the reciprocating piston type, and more particularly to improvements in the rotation mechanism usually incorporated in such rock drills for rotating the drill steel.

An important object of the invention resides in the provision of a rotation mechanism for rock drills having component parts of relatively simple design which may readily be assembled and disassembled without necessitating the use of special tools.

Another object of the invention is to provide a rotation mechanism of the above character that is capable of instantaneous action to effect rotation of the drill steel upon movement of the piston in one direction whereby the cutting edges of the former are moved appropriately between successive blows so that maximum efficiency in drilling is secured.

A further object of the invention is to provide a rock drill with a rotation mechanism that comprises relatively few parts, each of which is characterized by simplicity and ruggedness of construction thereby minimizing initial cost of manufacture and rendering unlikely damage other than resultant from ordinary use.

A still further object of the invention is to provide a rotation mechanism of the above character including the use of radially slidable plungers which cooperate with a specially designed head to effect rotation of the piston and which will provide a positive action for the plungers while eliminating the use of springs or the like for normally urging the plungers into operative engagement.

Other objects and advantages more or less ancillary to the foregoing reside in the specific construction and aggroupment of the elements peculiar to this structure, as will become apparent from a more complete examination of this specification.

In the drawing which illustrates the invention:

Fig. 1 is a side elevational view, partly in section, of a rock drill embodying the features of the present invention.

Fig. 2 is an enlarged horizontal sectional view taken substantially on line 2—2 of Fig. 1.

Fig. 3 is a view similar to Fig. 2 illustrating the parts in another position.

Fig. 4 is a detail sectional view taken substantially on line 4—4 of Fig. 2.

Referring to the drawing for a more detailed description thereof, a rock drill embodying the features of the present invention is generally designated by the reference numeral 8 and includes

a cylinder 9 formed with a piston chamber 10 in which is reciprocably mounted a piston 11. The piston 11 is formed with a shank 12 extending downwardly therefrom and slidable through a bushing 13, which bushing forms the lower end of chamber 10.

A front housing 14 is clamped to the cylinder 9 by means of bolts 15, in which is mounted the usual chuck sleeve and bushing (not shown) adapted to receive the shank of a drill steel 16 which is mounted in said bushing against relative rotation thereto. The shank 12 of the piston 11 is normally splined with the chuck for transmitting rotation thereto in a manner well known in this art.

The upper end of the cylinder 10 is formed with a counterbore 17 on the bottom of which rests a valve block 18. Seated on the valve block 18 is a valve casing 19 within which is reciprocably mounted a fluid actuated valve 20 for controlling the admission of fluid to alternate ends of the cylinder 10. The improved rotation mechanism, to be hereinafter more fully described, is generally designated by the numeral 21, the same being disposed within the counterbore 17 above the valve casing 19. A bearing plate 22 is seated upon the mechanism 21 engaged by a back head 23 which is clamped thereon through the side rods 15. A throttle valve (not shown) is mounted in the back head 23 and is operated by the lever 24 for controlling the admission of fluid to the valve casing 19 from where, under the control of the valve 20, it travels to alternate ends of the cylinder 10 for actuating the piston 11 in a manner well known in the art.

The rotation mechanism, in accordance with the present invention, includes a ratchet ring 25 resting on the valve casing 19 and held against rotation relative to the cylinder 9 by a dowel pin 26. The ring 25 is formed with internal teeth 27. A rifled or helically splined stem 28 extends upwardly from the piston 11 and cooperates with a rifled nut (not shown) screwed within the head of the piston for rotating the same. The rifled stem 28 extends through the valve block and casing 18 and 19, respectively, and carries a head 29 which is encircled by the ratchet ring 25. A floating ring 30 is mounted between the head 29 and ratchet ring 25, the ring 30 being formed with a plurality of spaced slots 31 containing plungers 32 adapted to engage the teeth 27 of the ratchet ring 25.

The inner periphery of the ring 30 is formed with a series of inwardly extending teeth 33 having right angular bearing surfaces 34 adapted to

be engaged by complementary teeth 35 formed on the outer periphery of the head 29. The plungers 32 are preferably arranged so that one plunger is disposed between a pair of teeth 34 and adjacent the side opposite the bearing surfaces 34. In the formation of the teeth 33, one wall 36 thereof slants inwardly for a predetermined distance and is united with the right angular bearing surface 34 through an arcuate surface 37.

As before indicated, the teeth 35 of the head 29 engage the teeth 33 of the ring 30, said teeth 35 being likewise formed with right angular bearing surfaces 38. The periphery of the teeth 35 is of such contour as to be in constant engagement with the inner wall of the ring 30, as clearly shown in Figs. 2 and 3. The area of the head 29 between the teeth 35 is formed with a pair of continuous cam surfaces 39 and 40, adapted to alternately engage the plungers 32 and arcuate surfaces 37 of the teeth 33. Rotation of the head 29 in a clockwise direction in Fig. 2 will effect engagement of the cam surfaces 39 and 40 with the plungers 32 to slide the latter outwardly into engagement with the gear teeth 27. However, rotation of the head 29 in a counterclockwise direction in Fig. 3 will bring the right angular bearing surfaces 34 and 38 of the teeth 33 and 35, respectively, into engagement permitting withdrawal of the plungers 32 from the gear teeth 27, whereby the head 29, ring 30 and rifled stem 28 are free to rotate in unison.

In the operation of the mechanism, as the lever 24 is actuated to open the throttle valve, motive fluid therefrom is free to flow to the valve 20 where it is alternately admitted into the ends of the piston chamber 10 for effecting reciprocation of the piston 11 and the consequential delivery of impacts on the drill steel 16.

As shown in Fig. 1, the stem 28 is provided with a high hand helical spline which cooperates with a similar spline provided in the rifled nut screwed within the piston 11, thereby tending, during the strokes of the piston toward the valve block 18, to rotate the stem 28 and its head 29 in a clockwise direction in Fig. 2. Assuming that the piston 11 has completed its forward stroke, on the return or rearward stroke, the stem 28 and head 29 will begin to turn in a clockwise direction. As the head 29 is rotated, the cam surfaces 39 and 40 contact the plungers 32 urging said plungers outwardly into engagement with the ratchet teeth 27. Engagement of the plungers with the ratchet teeth will lock the ring 30 and head 29 thereby preventing further rotation of the stem 28 and head 29 in a clockwise direction, and causing the piston during its rearward strokes to rotate in the other direction. From the piston, rotation is transmitted to the drill steel 16 through the chuck sleeve and bushing (not shown) in the manner well known in the art.

During the forward strokes of the piston, the stem 28 and head 29 will rotate in a counterclockwise direction in Fig. 3 and the parts will move from the position shown in Fig. 2 to that shown in Fig. 3. At that time the right angular bearing surfaces 38 of the teeth 35 will contact the right angular bearing surfaces 34 of the teeth 33 to effect rotation of the ring 30 and disengagement of the plungers 32 from the ratchet teeth 27. As is to be understood, the plungers 32 are freely slideable within the slots 31 and, as the ring 30 is rotated by the head 29,

said plungers will be free to slide out of engagement with the ratchet teeth 27 since contact will then be had with the low spot of the cam surfaces 39 and 40 as clearly shown in Fig. 3.

5 In this instance, the piston 11 will be driven forwardly without rotation for delivering impacts to the drill steel in rapid succession.

From the foregoing explanation, it will be understood that an improved means has been 10 provided for automatically imparting rotation to the piston and drill steel so that the cutting edges of the steel are moved appropriately between successive blows so that maximum efficiency in drilling is secured. The teeth 35 and 15 cam surfaces 39 and 40 on the head 29 are formed so as to actively engage the teeth of the floating ring 30 and plungers carried thereby as said head is rotated in either a clockwise or counterclockwise direction during reciprocation of 20 the piston.

Although the foregoing description is necessarily of a detailed character, in order to completely set forth the invention, it is to be understood that the specific terminology is not intended 25 to be restrictive or confining and it is to be further understood that various rearrangements of parts and modifications of structural detail may be resorted to without departing from the scope or spirit of the invention as herein claimed.

I claim:

1. In a rock drill, a cylinder having a piston 28 reciprocable therein and capable of rotation, a ratchet ring fixedly mounted in said cylinder, a rotation mechanism for said piston including a rifled stem operatively associated therewith, a head on said stem, a member disposed between said head and ratchet ring and movable with said head, and means carried by said member 35 adapted to engage said ratchet ring for effecting rotation of said piston during its strokes in one direction.

2. In a rock drill, a cylinder having a piston 45 reciprocable therein and capable of rotation, a ratchet ring mounted in said cylinder, a rotation mechanism for said piston including a rifled stem operatively associated therewith, a head on said stem, a ring freely mounted between said head and ratchet ring, plungers slidably carried by said ring adapted to engage said ratchet ring during the strokes of said piston in one direction, and means forming a part of 50 said head for urging said plungers into engagement with said ratchet ring, whereby rotation of said piston is effected during its strokes in one direction.

3. In a rock drill, a cylinder having a piston 60 reciprocable therein and capable of rotation, a ratchet ring mounted in said cylinder, a rotation mechanism for said piston including a rifled stem operatively associated therewith, a head on said stem, a ring freely mounted between said head and ratchet ring, plungers slidably carried by said ring adapted to engage said ratchet ring 65 during the strokes of said piston in one direction, a series of teeth formed on the inner periphery of said ring, a series of teeth formed on the outer periphery of said head adapted to engage said ring teeth during the strokes of said piston in one direction, and cam means on said head for urging said plungers into engagement with said ratchet ring, whereby rotation of said piston is effected during its strokes in one direction.

4. In a rock drill, a cylinder having a piston

reciprocable therein, a ratchet ring fixedly mounted in said cylinder, a rotation mechanism for said piston including a rifled stem operatively associated therewith, a head on said stem, a member disposed between said head and ratchet ring and rotatable with said head in one direction only, a series of spaced radially slidable plungers carried by said member and adapted to

engage said ratchet ring during the strokes of said piston in one direction, and means on said head for urging said plungers radially into engagement with said ratchet ring during said one direction of the piston for locking said head and rifled stem to permit rotation of said piston in said one direction.

EARL B. LEAR.
